UNITED STATES PATENT OFFICE.

KALEEL TEEN, OF JERSEY CITY, NEW JERSEY.

DESIGN FOR PRINTED CRAPE.

42,826.

Specification for Design. Patented July 23, 1912.

Application filed April 3, 1912. Serial No. 688,296. Term of patent 3½ years.

To all whom it may concern:

Be it known that I, KALEEL TEEN, a citizen of the United States, residing at No. 34 Fulton avenue, in the city of Jersey City, in the county of Hudson and State of New Jersey, have invented a new, original, and ornamental Design for Printed Crape, of which the following is a specification, reference being had to the accompanying drawing, forming part thereof.

The drawing is a plan view of a portion of printed crape showing my design.

I claim:

The ornamental design, for printed crape as shown.

Dated, New York, February 28th, 1912.
KALEEL TEEN.

Witnesses:

CHARLES P. SANFORD,
EDWARD N. DANFORTH.
